[57] **CLAIM**

The ornamental design for a housing for a portable telephone capable of hanging from a remote object, as shown and described.

DESCRIPTION

FIG. 1 is a top perspective view of a housing for a portable telephone capable of hanging from a remote object showing my new design;

FIG. 2 is a left side elevational view thereof, the right side being a mirror image of the left side;

FIG. 3 is a front elevational view thereof;

FIG. 4 is a top plan view thereof;

FIG. 5 is a bottom plan view thereof; and,

FIG. 6 is a rear elevational view thereof.

In FIG. 1, an antenna, keypad, receiver and speaker holes and horizontal rod are shown in broken lines as conventional environmental elements which do not constitute part of my new design.
